CLAIM

The ornamental design for a wheel, as shown and de-
scribed.

DESCRIPTION

FIG. 1 is a perspective view of my new wheel design,
with the hub cap removed;

FIG. 2 is a side-elevational view thereof;

FIG. 3 is a front-elevational thereof;

FIG. 4 is a rear-elevational view of my new wheel
design, with or without the hub cap;

FIG. 5 is the perspective view of FIG. 1 with the hub

cap in place; and
FIG. 6 is the front-elevational view of FIG. 3 with the
hub cap in place.
